UNITED STATES PATENT OFFICE

KARL HUFFELMANN, OF MUHLHEIM-RUHR-HEISSEN, GERMANY; MARIANNE HUFFELMANN, ADMINISTRATRIX OF SAID KARL HUFFELMANN, DECEASED, ASSIGNOR TO HUGO SCHRÖDER, OF ESSEN, GERMANY

COKE OVEN

Application filed September 28, 1926, Serial No. 138,149, and in Germany April 28, 1926.

My invention relates to improvements in coke ovens, and more particularly to the construction of the flues.

In coke ovens now in use with vertical flues having a burner at their lower ends, the upper part of the oven is apt to be heated less than the lower part; so that the operation of coking is finished in the bottom sooner than at the top. A condition like this constitutes a serious disadvantage, and numerous efforts aiming at improvement have been made.

According to this invention, a more uniform and equal heating of the top and bottom portions of a coke oven is secured by providing in the upper parts of the flues which pass through the walls of the chambers, suitable projections which reduce the cross-section of the flues or passages and increase the indirect heat transmission by radiation. Due to the reduction of the cross-section of the passages, an increased rate of flow through the flues or passages takes place and thus the heat transmission is increased. The indirect heat transmission is materially greater, because the projections in the upper part of the flues do not touch the walls of the chamber and are brought to a higher temperature due to the reduced heat transmission. The heat radiation increases with the fourth power of the absolute temperature so that a few degrees of increase of temperature means a great difference in the result. The size of the projections increases gradually towards the top and the heat transmission in the upper part of the flues is equal to that in the lower part; even though in the lower part the direct heat transmission is greater than in the upper part because of the higher temperature of the gases of combustion and of the flame of the burners.

To compensate the coking in the various sections of the oven, a newly discharged chamber and a newly filled adjacent chamber can be worked together. In this field two adjacent sections of a coking oven should not be discharged or emptied at the same time, or one shortly after the other. Instead, the operator always empties a chamber and fills it up again alongside a chamber where coking is proceeding and has nearly been completed. These adjacent chambers or sections

have a strong heating action on each other because heat is radiated from the heated chamber to the cold chamber. According to this invention, such radiation between a hot chamber and a cold chamber is avoided in the upper part of the wall by means of the projections in the flues or passages within said wall, such projections acting like screens so that only the lower part of a hot chamber can give up a part of its heat to a newly filled chamber by radiation.

For the purpose of explaining the invention an example embodying the same has been shown in the accompanying drawings, in which the same letters of reference have been used in all the views to indicate corresponding parts. In said drawings,

Fig. 1 is a fragmentary longitudinal vertical section through the upper part of a coke oven embodying vertical flues in accordance with the present invention;

Fig. 2 is a fragmentary vertical cross section through a coking chamber and heating walls, and as well through the regenerator in the lower part of the coke oven.

Fig. 3 represents a horizontal cross section through a coking chamber and the adjacent heating walls; and

Fig. 4 is a fragmentary cross sectional view showing a modification in the construction of the heating wall.

In the examples shown in the drawings the coke oven comprises horizontal coking chambers *k* separated from each other by heating walls having vertical flues *a*, the burners *b* being provided at the bottom parts of the said flues. At their bottom parts the flues are separated by plane transverse walls *c*, while at the top parts the transverse walls are composed of bricks *d* formed with lateral projections *e* or *f*, the form of the said projections being such that the heating surfaces *g* of the longitudinal heating walls *h* and *i* are not reduced in area. By thus reducing the cross-sectional area of the flues, the velocity of the gases is increased, which results in an increased indirect transmission of heat by radiation, and finally in a reduction of the radiation from one side wall of the flue to the other. The heat transmitted from the

heating gases to the projecting portions *e* and *f* can not be directly transmitted to the coking chambers. Thereby the temperature of the said projecting portions is increased 5 as compared to the temperature of the side walls of the flues, so that they transmit heat by radiation to the said side walls. The radiation from one side wall to the other of each flue is prevented because the said projections provide screens. Preferably the 10 projecting portions are disposed so that they do not intersect the direction of the burners. By the said combined actions of the projecting portions *e* and *f* the transmission of heat 15 is increased in the top parts of the flues, so that the difference of the heating effect of the gases on the top and bottom parts of the coking chambers is compensated.

In coke ovens having narrow coking 20 chambers the flues are comparatively broad, because regenerators of a certain size must be disposed below the ovens, and the height of the said regenerators can not be increased at will in view of the strength of the structure. In ovens of this type my improved 25 structure of the flues is particularly important.

While in describing the invention reference 30 has been made to particular examples embodying the same I wish it to be understood that my invention is not limited to the constructions shown in the drawings or to the use thereof in ovens of the class referred to. Further, I wish it to be understood that my 35 improved construction of the heating walls may be generally used in ovens provided with heating chambers, and that the invention is not limited to the use of the said heating walls in coking ovens. The projections 40 are directly opposite each other excepting when projections of the form shown at *f* are employed they are not placed opposite each other but one is near the one wall *h* and the other nearer to the opposite wall *h*. 45 These projections *f* are shown as having the form of ribs presenting one face squarely to the adjacent wall, the other face being inclined.

I claim:

50 1. A coke oven heating wall construction including vertical opposing side walls and vertical opposing transverse walls connecting the side walls and forming vertical flues for 55 the flow upwardly of heating gases, longitudinal projections on the transverse walls along the upper reaches of the flues, reducing the cross sectional area of the upper reach of each of the flues so that the cross-sectional 60 area of the upper reach of the flue is materially less than that of the lower reach of the flue, the positions of said projections being such with relation to the side walls that the heating surfaces of the latter remain undiminished in extent to the upward flow of 65

heating gases through the upper narrowed reaches of the flues.

2. A coke oven heating wall construction including vertical opposing side walls and vertical opposing transverse walls connecting 70 the side walls and forming vertical flues for the flow upwardly of heating gases, longitudinal projections on the transverse walls along the upper reaches of the flues, extending into the flues and reducing the cross sectional area of each of said flues, said projections being located between the side walls and leaving the heating surfaces of the side walls fully exposed to the upward flow of 75 gases through the reduced upper reaches defined by the side walls, transverse walls and projections.

3. A coke oven heating wall construction including confronting side walls and confronting transverse walls connecting the side 80 walls and forming a vertical flue, longitudinal projections on the confronting faces of the transverse walls along the upper reach of the flue, said projections extending toward each other and into the flue and being spaced 85 from both of said side walls and reducing the cross sectional area of the upper reach of the flue so that the cross-sectional area of the upper reach of the flue is materially less than that of the lower reach of the flue. 90

In testimony whereof I hereunto affix my signature.

KARL HUFFELMANN.
